Morsell & Keeney.

ATTORNEYS.

UNITED STATES PATENT OFFICE.

ARVIN THEODORE LANGJAHR, OF COLBY, WISCONSIN.

VISIBLE-RECORD FILE.

Application filed June 26, 1922, Serial No. 570,968. Renewed January 11, 1926.

To all whom it may concern:

Be it known that I, ARVIN THEODORE LANGJAHR, a citizen of the United States, and resident of Colby, in the county of Clark and

5 State of Wisconsin, have invented new and useful Improvements in Visible-Record Files, of which the following is a description, reference being had to the accompanying drawings, which are a part of this specification.

10 This invention relates to a visible record file for index cards and other similar records and has for its object to provide a file construction in which the various cards or 15 papers may be swung to a visible position without removal from the case.

15 A further object of the invention is to provide a construction whereby the card members or other records are borne by suitable holders, which holder members are removably pivoted within the case and which members serve to strengthen and support the card members.

20 A still further object of the invention is to provide a construction of the type described which will be comparatively simple and inexpensive to manufacture and more efficient in operation than those which have been heretofore proposed.

25 30 With the above and other objects in view which will appear as the description proceeds the invention consists in the novel details of construction and combinations of parts more fully hereinafter disclosed and 35 particularly pointed out in the accompanying claims.

35 Referring to the accompanying drawings in which like numerals designate like parts in all the views;

40 Fig. 1 is a side elevational view of a file case made in accordance with the present invention, showing a plurality of record cards and card holders in place therein;

45 Fig. 2 is a plan view of the parts shown in Fig. 1;

Fig. 3 is a detail perspective view of one of the card-holder members; and,

50 Fig. 4 is an elevational view of one of the card members illustrating the perforations formed therein for attaching the same to the card-holding member illustrated in Fig. 3.

55 The holding case comprises a box-like structure 5 having side walls 6, end walls 7, and a bottom 8. The side walls 6 are provided with a plurality of vertically extending slots 9 suitably spaced along the upper-

most edge thereof, the lower portions of the said slots terminating in the enlarged substantially circular apertures 10, as will be clear from Fig. 1.

60 The said slots 9 and apertures 10 are arranged in transverse alignment and are adapted to receive the pins or trunnions 11 carried by the lower portion of each card-holding member 12, see Fig. 3. These said card-holding members are preferably stamped of sheet metal or other similar material and their upper corners are provided with the ears or projections 13 adapted to engage the upper surface of the side walls 6 70 as is clearly indicated in Figs. 1 and 2.

75 The said members 12 are further provided with the tongues 14 which are stamped out substantially as shown, which tongues are adapted to engage the holes or apertures 15 provided in the upper portions of the card or other record members 16, see Fig. 4.

80 As will be noted from Figs. 3 and 4, the projecting tongues 14 of the members 12 are provided with enlarged substantially circular upper portions 17 and the relatively narrower lower portions 18, while the apertures 15 and card member 16 are provided with the substantially circular lower portions 19 and the reduced upwardly extending portions 20.

85 The said cards are applied to the card-holding members by introducing the enlarged portion 17 of the tongues 14 through the enlarged portions 19 of the apertures 15 in the cards 16, whereupon the latter may be moved downwardly relatively to the body of the card-holding members 12, so that the reduced upper portions of the holes 15 engage the reduced lower portions of the tongues 18.

90 It thus results that the card member 16 may be quickly and efficiently attached to the card-holding members 12 and they will be securely held in place thereon while at the same time permitting its ready removal therefrom when it is desired to change the cards.

95 In use the card member 16 is attached to the holding member 12 as above described, and the pins or trunnions 11 of the latter members are then inserted through the slots 9 in the side walls 6 of the casing member 5 and occupy the enlarged circular apertures 10 in the said side wall 6.

100 The said record members normally occupy the positions illustrated in Figs. 1 and 2 with the extensions or ears 13 of the card-

holding members 12 resting upon the uppermost surfaces of the side walls 6. However, when it is desired to consult the records carried by the card members 16 the said members, together with their holders 12, may be readily swung about the trunnions 11, as indicated in Figs. 1 and 2, to a substantially vertical position whereupon the records carried by the said cards may be rendered 10 readily visible.

It is obvious that those skilled in the art may vary the details of construction as well as the arrangement of parts without departing from the spirit of the invention, and 15 therefore it is not wished to be limited to the above disclosure except as may be required by the claims.

What is claimed is:

1. In a device of the class described the 20 combination with a casing having walls provided with aligned slots, of a plurality of record-supporting members having trunnions adapted to removably engage said slots, said supporting members being also 25 provided with ears for engaging said walls to limit the movement of said members and

with integral laterally and upwardly projecting tongues having enlarged upper portions and reduced lower portions; and record-bearing members detachably secured to 30 said tongues of said supporting members.

2. A record-supporting member for filing systems comprising a body portion provided with trunnions for pivotally engaging a filing casing, ears for limiting its movement 35 in said casing, and means comprising integral laterally and upwardly bent tongues having enlarged heads and reduced connecting portions for readily detachably holding 40 a record-bearing member.

3. A visible record file device comprising a record-supporting member having a body provided with integral offset upwardly-projecting tongues, said tongues being provided with enlarged heads and reduced connecting 45 portions; and a record-bearing member provided with apertures having enlarged and reduced portions adapted to receive corresponding portions of said tongues.

In testimony whereof, I affix my signature.

ARVIN THEODORE LANGJAHR.
